SPINNING CHARM OR THE LIKE ARTICLE

Stanley Zweig, Elmont, N. Y.

Application August 2, 1949, Serial No. 4,239

Term of patent 14 years

(Cl. D45—17)

To all whom it may concern:

Be it known that I, Stanley Zweig, a citizen of the United States, and resident of Elmont, in the county of Nassau, State of New York, have invented a new, original, and ornamental Design for a Spinning Charm or the Like Article, of which the following is a specification, reference being had to the accompanying drawing, forming a part thereof, and of which

Figs. 1 and 2 are front and side elevational views, respectively, of a spinning charm, showing my new design, and

Fig. 3 is a front elevational view similar to Fig. 1 showing the spinner rotated through 180 degrees with respect to that shown in Fig. 1. The front and rear of the charm are identical.

I claim:

The ornamental design for a spinning charm or the like article, as shown and described.

STANLEY ZWEIG.
